UNITED STATES PATENT OFFICE

168,000

MANUALLY SET PORTABLE REGISTER

Edwin C. Rosenberg, Milwaukee, Wis.

Application January 25, 1951, Serial No. 13,946

Term of patent 14 years

(Cl. D52—1)

To all whom it may concern:

Be it known that I, Edwin C. Rosenberg, a citizen of the United States of America, residing at Milwaukee, in the county of Milwaukee and State of Wisconsin, have invented a new, original, and ornamental Design for a Manually Set Portable Register, of which the following is a specification, reference being had to the accompanying drawing, forming part thereof.

In the drawing:

Fig. 1 is a front perspective view of a manually set portable register, showing my new design.

Fig. 2 is a perspective view of the design shown in Fig. 1 as viewed from the rear.

Fig. 3 is a cross-section taken on line 3—3 of Fig. 2.

Fig. 4 is a front elevation; and

Fig. 5 is a plan view.

I claim:

The ornamental design for a manually set portable register, as shown.

EDWIN C. ROSENBERG.
